FIRE EXTINGUISHER MEANS

David Moffat Myers, Larchmont, N. Y.

Application May 14, 1943, Serial No. 486,976

5 Claims. (Cl. 299—96)

The invention relates to liquid dispensing or discharging means, particularly fire extinguisher means employing a chemical extinguishing liquid such as carbon tetrachloride; and it is concerned more especially with an attachment for converting a commercial container for such liquid into a fire extinguisher whereby the liquid contents may be delivered and projected a considerable distance. Ordinarily, containers for such liquid are in the nature of tin-plate cans of quart or larger size having a screw-cap or seal on a neck of the container through which neck the fluid may be emptied when the screw-cap is removed.

The invention has for an object an attachment or substitute closure member for the usual screw-cap of such containers whereby the can is converted into an effective fire-extinguishing means, the original cap being discarded.

A further object of the invention is to provide a novel cap member designed to replace the standard screw-cap of such containers.

It has been found that after more or less extended periods of time certain manually-operated pumping types of fire extinguishers occasionally stick and bind sufficiently to render the extinguisher useless in an emergency; and it is another object of the invention to provide a fire extinguisher attachment having no moving parts in the liquid, thereby eliminating the usual difficulty resulting from corrosion of moving parts in liquid.

Still another object of the invention is to provide an extinguisher which will eliminate the inconvenient necessity of refilling, as in the case of the usual type of fire extinguisher after its charge of fluid is exhausted, the novel attachment requiring merely the throwing away of the empty can and the application of the attachment to a new and full can.

The invention has for an object, also, to provide a construction which will prevent spillage as well as evaporation of the contents of the can and also prevent contact of the liquid with the means for providing pressure thereon.

The novel attachment, moreover, obviates the purchase of an expensive and costly container forming part of the usual type of hand-operated, chemical fire extinguisher, it being necessary merely to purchase the chemical in an ordinary can and attach the novel device thereto to convert the same immediately into an effective fire extinguisher.

In carrying out the invention, the usual sealing cap which is threaded on the neck of a can of the liquid is discarded and there is substituted there-

for a novel closure member. This closure member comprises a cap member designed to fit over the said neck and includes a head portion to seal the container, said head portion being provided with air inlet and air outlet ports for connection with an external bulb for introducing air under pressure into the container and carried by said closure member.

A further means, such as an ejector pipe, also carried by the closure member, extends substantially to the bottom of the container and is adapted to communicate with a nozzle port of the head for discharging the contents of the container when the air under pressure is applied. A plug valve element fitted to oscillate within the head serves to control communication through the said ports as well as through a further and relief port of the head designed to provide for the escape from the container of any air under pressure when it is desired to discontinue the discharge of liquid, the arrangement being such that the liquid discharge is cut off prior to the opening of the relief connection.

The nature of the invention, however, will best be understood when described in connection with the accompanying drawing, in which:

Fig. 1 is a plan view and Fig. 2 a rear elevation of the novel attachment applied to a container.

Fig. 3 is a vertical section of the container with the attachment applied and shown in elevation.

Fig. 4 is a fragmentary end elevation of the container with the novel attachment applied.

Fig. 5 is a vertical section of a modified form of the attachment.

Figs. 6, 7, and 8 are vertical sections on an enlarged scale of the novel attachment showing different positions of the controlling plug valve, the compression air bulb connection and liquid ejector pipe being broken away.

Referring to the drawing, the novel attachment is shown in the nature of a cap member 10 threaded to fit on the correspondingly threaded neck 11 of a container 12, the latter embodying the usual tin-plate can of quart or larger size containing the desired liquid to be discharged, for example, a fire-extinguishing liquid or chemical such as carbon tetrachloride. The usual cap (not shown) furnished with such can is to be discarded and replaced by the cap 10 which is screwed down to form an air-tight joint. The novel cap member, as shown more clearly in Figs. 6 to 8, comprises a head portion 13 formed integrally with the threaded portion 10; or, as

shown in Fig. 5, the threaded cap portion 10' may be constructed as separate from the head portion 13' which is then designed to extend through a perforation 10" in the top of said threaded portion. A washer 13" may be introduced between the top of said threaded portion 10' and the top of the neck 11 of the container to afford an air-tight seal thereat. In this embodiment, proper alignment of the head portion 13' may more readily be secured by holding said head portion in the desired angular position while screwing on the threaded portion 10' against washer 13".

There is provided transversely through this head portion in either case a central bore 15 from which extends through the head an air inlet port 16 with pipe extension 17. To the latter is designed to be connected suitable air supplying means such as a hose or flexible tube 18 communicating with a compression air bulb 19 designed to introduce air under pressure to the port 16. A further air port 20 communicates with the transverse bore 15 and through the lower end of the cap member is designed to afford an outlet port for air into the container as received from the compression bulb 19. The control of this supply is effected by means of a valve plug 25 fitting the bore 15 and oscillatable manually, for example, through an arc of 90° by means of a handle member 26 attached to a journal 27 there-of extending beyond the head 13.

In addition to the aforesaid ports 16 and 20, there are provided further ports 30 and 31 extending from the bore 15 through the head, the former constituting a nozzle port for discharge of liquid from the container 12 and the latter an ejector port having the extension or ejector tube 32 which is carried by the head and terminates substantially at the bottom of the container when the head is applied to the neck 11, as shown in Fig. 3 of the drawing.

Due to the fact that a device of the nature set forth will be subject to rough and careless handling under various conditions, it is preferred, in order to protect and maintain the required diameter of the outlet of the discharge port 30, to counterbore the same at its outer end, as indicated at 33, so that bruising of the mouth of the jet port 30 cannot occur. Any injury to the mouth of this jet port would otherwise result in restricting or eliminating the discharge of fluid or in diverting its direction, thus seriously impairing the efficiency of the extinguisher.

There is provided in said head 13 also a relief port 35 adjacent the nozzle port 30 for discharging air under pressure in the container when closing off the said nozzle port and the air inlet and outlet ports. This control of the various communications involved is indicated more clearly in Figs. 6-8, inclusive, Fig. 6 illustrating the handle 26 in the horizontal or closed position wherein the valve plug 25 seals off all of the aforesaid ports.

When the handle is elevated in the direction of the arrow, Fig. 6, to the substantially vertical position shown in Fig. 7, two through ports 36 and 37 of the valve plug are arranged to afford communication respectively between the air inlet and outlet ports 16, 20 and the nozzle and ejector ports 30, 31. The through port 36 to this end is right-angled and, as indicated in said Fig. 7, direct communication will be afforded thereby between the air compression bulb 19 and the interior of container 12 so that air and pressure will be introduced over the surface of the liquid 38 in the container to force the same outwardly through

the ejector pipe 32, its port 31, and the port 37 to the nozzle port 30 from which it is discharged for use.

To seal the container, it is necessary merely to move the handle in the opposite direction, as indicated by the arrow, Fig. 8, until it assumes again the horizontal position indicated in Fig. 6. During this return movement, however, it assumes momentarily an intermediate position, as indicated in Fig. 8, wherein the port 37 will register both with the relief port 35 and the air outlet port 20 so that a direct communication is afforded between the interior of the container and the atmosphere, thereby relieving any pressure in the container prior to the complete sealing-off of the latter.

This relief of pressure within the container when the device is not in use is of considerable importance in that stress on the seams of the can 20 and cover member joints is obviated, with consequent elimination of leakage and loss of the volatile contents.

The novel attachment makes it possible to convert quickly an ordinary commercial can of the fire-extinguishing liquid into a very effective fire extinguisher, with which it is possible to throw a stream some fifteen feet from the container upon compressing and working the bulb in the usual manner to supply air under pressure over the liquid. When the contents are exhausted, it is necessary merely to unscrew the attachment and apply the same to a further can to replenish the supply.

The attachment is constructed such that there will be no moving parts normally in contact with the liquid and subject to corrosion, nor will the bulb be contacted by the liquid at any time; and leakage and/or evaporation of the contents during storage is insured against in the provision of the sealing means associated with the ports, as well as in the provision of the relief port. The novel attachment is of relatively inexpensive construction and is readily and quickly applied without the use of any tools.

I claim:

1. Liquid-ejecting means and substitute closure member for the sealing cap of a container, adapted for dispensing a fire-extinguishing liquid from the said container through the neck thereof, comprising a cap member designed to fit removably over the said neck and including a head portion with compression air bulb attached thereto, said head being provided with a central transverse bore having an air inlet port communicating therewith and with the air bulb and having also an air outlet port for communication with the interior of the container, said head being further provided with a nozzle port extending from the transverse bore through the head, and with an adjacent pressure relief port extending from the transverse bore through the head, an ejector pipe carried by said head to extend therefrom into the container substantially to the bottom thereof, its outer end terminating at the transverse bore of the head, and a valve plug oscillatably fitted within the said transverse bore having a through port adapted to register in the open position of the plug respectively with the outer end of the ejector tube and the inner end of the nozzle port and in an intermediate position with the air outlet port and the relief port, said plug having a further through port adapted in the first-named open position of the plug to establish communication between the air inlet port and the air outlet port and in the intermediate and closed

positions of the plug interrupting such communication.

2. Liquid-ejecting means and substitute closure member for the sealing cap of a container, adapted for dispensing a fire-extinguishing liquid from the said container through the neck thereof, comprising a cap member designed to fit removably over the said neck and including a head portion with compression air bulb attached thereto, said head being provided with a central transverse bore having an air inlet port communicating therewith and with the air bulb, and having also an air outlet port for communication with the interior of the container, said head being further provided with a counterbored nozzle port extending from the transverse bore through the head, and with an adjacent pressure relief port extending from the transverse bore through the head, an ejector pipe carried by said head to extend therefrom into the container substantially to the bottom thereof, its outer end terminating at the transverse bore of the head, and a valve plug oscillatably fitted within the said transverse bore having a through port adapted to register in the open position of the plug respectively with the outer end of the ejector tube and the inner end of the nozzle port and in an intermediate position with the air outlet port and the relief port, said plug having a further through port adapted in the first-named open position of the plug to establish communication between the air inlet port and the air outlet port and in the intermediate and closed positions of the plug interrupting such communication.

3. Liquid-ejecting means and substitute closure member for the sealing cap of a container, adapted for dispensing a fire-extinguishing liquid from the said container through the neck thereof, comprising a cap member designed to fit removably over the said neck and including a head portion with compression air bulb attached thereto, said head being provided with a central transverse bore having an air inlet port communicating therewith and with the air bulb and having also an air outlet port for communication with the interior of the container, said head being further provided with a nozzle port extending from the transverse bore through the head, and with an adjacent pressure relief port extending from the transverse bore through the head, an ejector pipe carried by said head to extend therefrom into the container substantially to the bottom thereof, its outer end terminating at the transverse bore of the head, and a valve plug oscillatably fitted within the said transverse bore having a through port adapted to register in the open position of

the plug respectively with the outer end of the ejector tube and the inner end of the nozzle port and in an intermediate position with the air outlet port and the relief port, said plug having a further and right-angled through port adapted in the first-named open position of the plug to establish communication between the air inlet port and the air outlet port and in the intermediate and closed positions of the plug interrupting such communication.

4. Liquid-ejecting means and substitute closure member for the sealing cap of a container, adapted for dispensing a fire-extinguishing liquid from the said container through the neck thereof, comprising a cap member designed to fit removably over the said neck and including a head portion with compression air bulb attached thereto, said head being provided with a central transverse bore having an air inlet port communicating therewith and with the air bulb and having also an air outlet port for communication with the interior of the container, said head being further provided with a nozzle port extending from the transverse bore through the head, and with an adjacent pressure relief port extending from the transverse bore through the head, an ejector pipe carried by said head to extend therefrom into the container substantially to the bottom thereof, its outer end terminating at the transverse bore of the head, and a valve plug oscillatably fitted within the said transverse bore, providing with an operating handle swingable from a horizontal to a vertical position and having a through port adapted to register when the handle is in the vertical position respectively with the outer end of the ejector tube and the inner end of the nozzle port and in an intermediate position with the air outlet port and the relief port, said plug having a further through port adapted when the handle is in the vertical position to establish communication between the air inlet port and the air outlet port and in the intermediate and horizontal positions interrupting such communication.

5. In a device of the nature set forth: an oscillatable valve plug having a straight through port eccentrically disposed in the plug, said port being adapted to be positioned for registry of its one end successively with a fluid discharge port and with a relief port, all ports being in the same plane, and at its opposite end in both positions with the interior of a single container for discharging respectively liquid from said container and for venting the container.

DAVID MOFFAT MYERS.
